UNITED STATES PATENT OFFICE.

JAMES ROBERT PARRISH, OF NASHVILLE, TENNESSEE.

NAPKIN OR BIB HOLDER.

1,272,512.

Specification of Letters Patent. Patented July 16, 1918.

Application filed March 27, 1918. Serial No. 224,966.

To all whom it may concern:

Be it known that I, JAMES ROBERT PARRISH, a citizen of the United States, and a resident of Nashville, in the county of 5 Davidson and State of Tennessee, have invented certain new and useful Improvements in Napkin or Bib Holders, of which the following is a specification.

My invention is an improvement in napkin or bib holders, and has for its object to provide mechanism of the character specified for supporting a child's bib in proper position without the use of strings or pins, and so arranged that it may be easily placed or 15 removed, and which permits the use of a rectangular piece of cloth without the usual cut-out in the neck.

In the drawings:

Figure 1 is a front view of the improved 20 holder in closed position;

Fig. 2 is a similar view with the holder open;

Fig. 3 is a similar view showing a napkin or bib in place in the holder;

Fig. 4 is an end view showing the manner 25 of connecting the napkin;

Fig. 5 is an end view of Fig. 1, looking at one end; and

Fig. 6 is an end view looking at the other 30 end.

In the present embodiment of the invention, the improved holder, which is formed from wire bent to shape, consists of sections 35 7 and 8, which are integral at one end, being connected by a coil 3 as shown, and each of the said sections is provided intermediate its ends with a bent or arched portion 1 and 2, respectively.

At the opposite end from the coil 3 the section 40 7 has an angular portion 5, and the section 8 has a hook 4 for engaging the section 7 at the angular portion to hold the sections together in the position shown in Figs. 1 and 3. The portions 1 and 2 form, 45 when the sections 7 and 8 are closed, a circle, which is adapted to encircle a child's neck to hold the entire support in proper position.

The napkin, indicated at 9, has an edge 10 turned over and stitched down upon the body of the napkin as indicated at 11 to 50 form a loop at the said edge, the section 8 being passed through this loop. The teeth or roughened portions 6 prevent slipping of the bib or napkin, and it will be obvious that in place of the loop clamps might be 55 provided for attaching the napkin directly to the section 8. To place the napkin upon the child, the hook 4 is disengaged from the section 7, and the ring formed by the arched portions 1 and 2 is placed about the 60 child's neck, after which the hook is again engaged with the section 7. It is obvious that the teeth 6 might be dispensed with, being replaced by sections of rubber tubing. The sole purpose of these teeth is to prevent 65 slipping of the bib longitudinally of the section 8.

I claim:

1. A device of the character specified, comprising opposed clamping members of 70 resilient material connected at one end by a resilient coil, one of the members having a hook at the other end for engaging the other member, each of the said members having intermediate its ends an outwardly bent 75 portion coöperating when the members are closed together to form a ring for encircling a child's neck, one of the said members having teeth near each end for the purpose specified.

2. A device of the character specified, comprising opposed clamping members of resilient material connected at one end by a resilient coil, one of the members having a hook at the other end for engaging the other 85 member, each of the said members having intermediate its ends an outwardly bent portion coöperating when the members are closed together to form a ring for encircling a child's neck.

JAMES ROBERT PARRISH.
